CANDY PREFORMING MACHINE

Leo Latini and Edmond Latini, Chicago, Ill.; said
Edmond Latini assignor to said Leo Latini

Application February 5, 1947, Serial No. 726,574

24 Claims. (Cl. 107—8)

1

This invention relates to candy making machines and more particularly to candy preforming devices for producing hard candies in conjunction with handle sticks such as confections commonly termed suckers, although certain features thereof may be employed with equal advantage for other purposes. This invention is a continuation-in-part of my application Serial No. 467,091, filed November 27, 1942, and which eventuated into Letters Patent No. 2,431,489 dated November 25, 1947.

It contemplates more especially the provision of an improved, substantially greater capacity, and more efficient hard candy preforming machine, preferably though not essentially for producing candies having attached sticks associated therewith during the formation thereof.

Numerous types of candy preforming machines have heretofore been proposed, including machines for the production of candy consumed with the aid of a stick such as suckers, but these are intricate, comparatively slow and massive machines that entail a high unit cost by reason of their low production which is a factor of their intermittent operation, so that hard candy producing machines of a sucker type may be appreciably increased in capacity, continuous operation and novel structural instrumentalities have been provided to continuously produce preformed hard candies of a sucker type in large quantities without requiring the intricate and tedious operating characteristics of intermittent elements.

One object of the present invention is to simplify the construction and to improve the operation of devices of the character mentioned.

Another object is to provide improved candy preforming machines for producing hard candies of a sucker type with simple, compact and highly efficient instrumentalities.

Still another object is to provide a machine of a rotary table type with a plurality of complementary die members that are cooperatively actuated in timed relation to feed, preform, effect the association of a stick therewith and accomplish the ejection thereof for discharge in a continuity of high speed operations.

A further object is to provide hard candy preforming devices including complementary die elements that are actuated in timed relation at a continuous high speed to form hard candy confections in conjunction with a stick serving as a handling expedient therefor.

A still further object is to provide improved stick feeding means in conjunction with preforming die elements that are movable relative

2

to each other in timed relation with ejecting and discharge means responsive to a continuity of operations.

Still a further object is to provide candy and stick feeding instrumentalities in conjunction with complementary die elements that are movable relative to each other in timed relation to ejecting and discharge means responsive to the rotation of a table mount in the path of stationary cam tracks.

Other objects and advantages will appear from the following description of an illustrated embodiment of the present invention.

In the drawings:

Figure 22 is a sectional view taken substantially along line XXII—XXII of Figure 21.

Figure 23 is a side view in elevation of candy segment and feeding rollers viewed substantially along line XXIII—XXIII of Figure 1.

Figure 24 is a face view of the knocker actuator cam viewed substantially from line XXIV—XXIV of Figure 23.

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a frame work 10 having a frame top 11 supported by a plurality of corner legs or standards 12 to elevate the frame top 11 from the supporting floor so that a continuous strand or ribbon of plastic candy can be fed thereto, as will appear more fully hereinafter. An attendant guides the strand or ribbon of plastic candy from a sizing device of standard construction to a flared entrant orifice 13 defined between two confronting grooved and pegged rollers 14 and 15 (Figures 1, 2 and 23). The rollers 14—15 are vertically journaled in the stub shafts 16 and 17, respectively, so that the substantially semicircular grooved peripheries 18 of the rollers 14—15 will be in confronting edge contact as at 19 (Figures 2 and 23), to define the enclosed circular passage 20 that communicates with the flaring entrant orifice 13 conforming substantially with the shape of the strand or ribbon of plastic candy that is manually or automatically fed thereto.

The stub shafts 16—17 are journaled in a bearing bracket 21, and each shaft has spacer collars 22—23 thereon between which meshing spur gears 24—25 are mounted. The lower shaft 17 has a sprocket 26 on its extension 27 to re-

ceive a chain 28 thereover. The chain 28 extends to a sprocket 29 below the frame table 11 (Figure 2) for attachment to a shaft 30 journaled in bearing brackets 31—32 depending from the underside of the frame table 11.

It should be noted that the feed rollers 14—15 are intermittently rotated through a ratchet wheel 33 fixed to the end of the shaft 30 (Figures 2, 3 and 5). The ratchet wheel 33 cooperates with a pawl 34 provided on the end of a lever 35 which is pivoted on the shaft 30 (Figures 3 and 5) for oscillation responsive to a connected lever 36 operatively connected to a crank arm 37 that is rotated intermittent rotation of the feed wheels 14—15 as will appear more fully hereinafter.

In order to sever the continuous strand or ribbon of plastic candy 38 into segments 69 (Figures 12 and 13) for deposit into complementary die members, vertically reciprocal scissor operating shearing knives 41—42, attached to arms 43—44 by means of fasteners such as machine screws 45 (Figures 2 and 20), for vertical pivotal reciprocation about a mounting pin 46 in the path of the plastic candy strand or ribbon 38. The knives 41—42 operate during the dwell in the intermittently rotating feed rollers 14—15, and the knives 41—42 are thus timed therewith. It should be noted that the pivot pin 46 is carried by a bracket 47 fixed to the top of the frame table 11 (Figure 2). Offset actuator arm extensions 48—49 extend from the knife arms 43—44 beyond their pivot 46 to carry confronting vertical roller mounts 50—51.

The mounts 50—51 are provided with cam follower rollers 52—53 that coast with oppositely positioned cams 54—55 fixed to a shaft 56 (Figure 23). The shaft 56 is journaled in bearing brackets 57—58 fixed for support on the frame table 11. These knives 41—42 are normally subjected to a separating urge by an interconnecting spring 59 to maintain the follower rollers 52—53 in contact with their actuator cams 54—55 for positive cutting approach responsive thereto with the candy roll 38 therebetween.

A lever 60 is pivoted as at 61 to a mount 62 to carry a cam follower roller 63 in the path of a cam 64 which is also mounted on the shaft 56 to operate the lever 60 with its candy engaging curved bracket retainer 65 (Figure 20) at the extremity thereof to engage the candy roll 38 adjacent the knives 41—42 to progressively sever the candy roll 38 into segments or units 69 (Figures 12 and 13).

An elongated coil tension spring 66 is anchored at one extremity to a lug 67 projecting laterally from the lever 60 (Figures 2 and 23) while its other extremity is anchored to a lug 68 fixed to the frame 10, thereby normally urging the lever 60 with its bracket retainer 65 against the candy roll 38. The cam 64 operates to actuate the lever 60 to disengage the retainer 65 from contact with the candy roll 38 in timed relation with the operation of the feeding rollers 14—15 and the knives 41—42.

The lever 60 with its retainer bracket 65 is actuated momentarily in advance of the knives 41—42 so as to first hold the candy roll 38 against movement, and this occurs while the candy feeding rollers 14—15 are stationary. The feeding rollers 14—15 are intermittently rotated as will appear more fully hereinafter. During the movement of the rollers 14—15, the knives 41—42 are open and stationary. Upon the operation of the retainer 65 for engagement with the candy

roll 38, the knives 41—42 are actuated to produce successive segments or units 69.

The successive segments or units 69 are positively displaced downwardly into a rotary distributor 70 by a knocker lever 71 (Figures 1 and 23) which terminates in a bearing 72 fixed to an end of a countershaft 73. The countershaft 73 is supported in bearings 74—75 that extend from the brackets 57—58 supporting the bearings 57—58 which rotatively support the cam shaft 56. The countershaft 73 has a bearing 76 at its other end to support a radial furcated bracket 77 to which is mounted a cam follower roller 78. The cam follower roller 78 confronts a cam 79 fixed to the extremity of the cam shaft 56 which rotates to actuate the knocker lever 71 in synchronized timed relation to the operation of the retainer 65 and scissor-like operating knives 41—42 which are all cam actuated from the shaft 56. A spring 80 is tensioned between the bracket 77 and bearing bracket 58' by engagement with pins 81—82, respectively, to retain contact between the roller 78 and cam 79.

As the candy segments 69 are severed from the candy roll 38 responsive to the scissor-like operation of the knives 41—42, these are knocked downwardly by the lever 71 to a distributor 83 having a series of radial open cavities 84 open at their exterior end 85 (Figures 1 and 16). The radial cavities 84 in this instance eleven, are provided in a circular carrier 86 journalled about a vertical shaft 87 that extends downwardly through the frame table top 11. The cavities 84 of the distributor 83 have downwardly converging side and end walls 88—89 (Figure 16) which merge into the open cylindrical cavities 84 to receive the candy segments 69 therein as the knives 41—42 and knocker lever 71 are actuated in synchronized timed relation with the rotation of the distributor 83.

Each of the open cylindrical cavities 84 are provided with reciprocal piston plates 90 fixed to tubular guide rods 91 that telescope over radial rods 92 anchored in the hub of the carrier 86 (Figure 16). The tubular guide rods 91 have depending studs 93 which carry cam follower rollers 94 disposed in a cam groove 95 provided in the upper surface 96 of a circular cam body 97. The cam body 97 is fixed to the frame table 11 by means of fasteners 98. Consequently, as the distributor 83 rotates, the pistons 90 reciprocate to displace the candy segments 69 into the path of confronting forming dies as will appear more fully hereinafter.

In order to rotatably support the plurality of complemental die members for timed movement in conjunction with the candy feeding 14—15, severing element 41—42, and distributing instrumentalities 83—84, the frame top 11 has a depressed circular portion 100 (Figure 6) provided with an upstanding hub 101 having an axial bore 102 thereof to receive a vertical drive shaft 103 therethrough. The depressed circular portion 100 has an upstanding circular trough 104 defined by spaced circular walls 105—106 formed integral with the depressed frame top portion 100. The outer spaced wall 106 terminates in a horizontal surface 107 that has a depending peripheral flange 108 (Figure 2) extending therefrom to define the outer limits of the depressed frame top portion 100.

A pair of confronting die supporting table mounts 109—110 were fixed to the drive shaft 103 for rotation therewith, there being comple-

mental keys and key-ways 111—112 (Figure 6) provided therebetween so that rotation of the drive shaft 103 will insure the rotation of the confronting table mounts 109—110 that are maintained in spaced relation by a collar 113 (Figure 6). A ball bearing raceway 114 is interposed between the hub 101 of the depressed frame top 100, and the hub of the lower table mount 109 to insure smooth and high speed rotation of spaced table mounts 109—110 relative to the depressed frame top portion 100 and its hub 101 (Figure 6).

A plurality of die receiving compartments 115—116 are circumferentially spaced in vertically aligned relation in the table mounts 109—110 to receive a corresponding number of complemental die bodies 117—118, in this instance eleven in each of the table mounts 109—110. It should be observed that the die receiving compartments 115 in the lower table mount 109 communicate with the annular trough 104 formed in the depressed portion 100 of the frame top 11, and that the lower die bodies 117 are secured in the compartments 115 which are of complemental shape to serve as a support therefor. Similarly, the upper compartments 116 are provided with correspondingly shaped die bodies 118 that have an overlapping retaining plate 119 thereover the attachment thereof to the outer ends 120 of the upper mount 110 through the medium of threaded fasteners 121 (Figure 6).

Confronting die elements 122—123, which may be of any suitable shape and type, are provided with shanks 124—125 which are reciprocally mounted within somewhat larger bores 126—127 provided axially through the die bodies 117—118. Compression springs 128—129 comprising uniform helical convolutions of wire envelop the die shafts 124—125 below and above the die bodies 117—118, respectively, to normally urge the dies 122—123 to their inward extreme position relative to the die bodies 117—118. Suitable cam contact caps 130—131 are provided on the extremities of the die shafts 124—125 to serve as a stop for the springs 128—129 and also as cam followers which ride over lower and upper cam surfaces 132—133 (Figures 2, 6, and 8).

The cam surfaces 132—133 comprise the actuators for the dies 122—123, respectively, and these are formed on cam bodies 134—135 (Figures 2 and 6) serving as actuator tracks over which the die shank cam follower caps 130—131 ride over predetermined portions of their arc of travel. It should be noted that a cam 134' (Figure 6) has an oil immersed track complementary to the lower cam follower caps 130 to positively return the lower dies 122 to their initial separated position. This assists the springs 128 to accomplish the movement of the dies 122. A plurality of stick receiving slots 136, in this instance one, is provided in the outer peripheral surface 137 of the lower table mount 109 along a radial median line of each lower die receptacle 115, to receive handle sticks 142 that extend inwardly to the center axis of the lower die element 122. To this end, each of the lower die bodies 117 are slotted as at 139 to communicate with the radial slots 136 provided in the outer surface 137 of the lower table mount 109 to accommodate the sticks 142 that are fed thereto as will appear more fully hereinafter.

The lower cam track 134 (Figure 6) is fixed to the bottom of the annular trough 104 at approxi-

mately, the circumferential position comprising substantially the sixth die position from the candy distributor feeding station 140 (viewed from Figure 1 and counting in a clockwise direction from the radial feeding position 140). At this position the cam track 134 would cause the lower die element 122 to be raised to its extreme upward position to eject the previously formed candy 141 (Figure 6) which is then rotated with the table mounts 109-116 to another position approximating the circumferential spacing of adjacent die elements 122-123 to complete the ejection of the preformed candy 141 on the sticks 142, which are impaled in timed relation with the candy segmenting and distribution to the dies 122-123 as will appear more fully hereinafter from a detailed description.

The upper die element 123 which is complementary to the lower die element 122 is previously actuated to effect the downward depression thereof against the lower die element 122 by virtue of the passage of the upper die shank caps 131 against the cam under surface 133 of the track 135 (Figure 8). The cam track 135 is suspended at both ends 143-144 (Figures 2 and 8) by upstanding threaded studs 145-146 which project from the cam track end bosses 147-148 to adjustably extend through bosses 149-150 provided in a triangular horizontal arm 151 of a vertical bracket 152 (Figure 2). The vertical bracket 152 is attached for support on the frame table top 11 by means of fasteners 153 extending through bracket ears 154 (Figures 1 and 2), and is positioned diametrically opposite the stick feeding and impaling instrumentalities (Figure 1) to be hereinafter described.

The inward cam track supporting stud 145 is pivoted to the cam track furcated boss 143 by means of a pin 155 while the outward tubular enlarged supporting stud 146 has a rod 156 guided therethrough by collar stops 157-158 to receive a coil spring 159 therebetween within the stud 146. The upper collar 158 is freely adjustable relative to the cam track supporting rod 156 for threaded engagement with the interiorly threaded tubular stud 146 to adjust the compression of the spring 159 which is supported with the rod 156 by its collar 157 initially resting on the flanged bottom 160 of the stud 146.

With this arrangement, the angularly extending upper cam track 135 is angularly yieldable upwardly about its pivot 155 against the compression of the spring 159.

The inward cam tracks supporting pivot 155 is vertically adjustable by means of threaded nuts 161-162 which engage the stud 145 on both sides of the vertical bracket arm boss 149 (Figures 2 and 6). The lower cam track 134 is also adjustably supported by means of a depending arm 163 (Figures 6 and 7) which depends downwardly through an opening 164 in the frame top portion 100 beyond the annular oil confining trough 104 therein (Figure 6). The offset arm 163 pivotally engages a depending bracket 165 fixed by means of fastener studs 166 to the underside of the frame top portion 100. A pin 167 pivotally connects the offset arm 163 to the bracket 165 which seals the openings 164 in the frame top portion 100 against the escape of oil 168 which lubricates the cam track 134. A hand knob 169 on a rod 170 enables the rotation of its enlarged threaded sleeve 170 within the frame top portion 100 to adjustably carry a reduced tip 171 within the annular trough 104 to engage the underside of the lower cam track 134 at a point spaced from its pivotal

5 offset arm 163. A packing box 172 envelops the rod 169, and it is attached to the underside of the frame top portion 100 to seal the threaded connection of the rod sleeve 170 against oil leakage.

Thus both the lower cam track 134 and the upper cam track 135 are pivotally, yieldably, and adjustably mounted to conform with the desired degree of power to be relatively exerted by the die elements 122-123. This can be controlled to meet the requirements of different types of candies as well as compensate for wear. The upper cam track 135 is positioned so that compression commences at the second die station from the distributor feeding station 140 and increases in degree to its extreme compression that is effected at substantially the fourth die station (viewed from Figure 1 and counting in a clockwise direction).

At substantially the fifth station from the feeding station 140, the upper die 123 is fully released and in the next adjacent station or substantially the sixth die position the lower cam track 134 begins to lift the lower die element 122 to accomplish the ejection of the completed candy 141 with the stick 142 in position (Figures 1 and 6). At the next adjacent position or substantially the seventh, a take-up mechanism 175 removes the completed candy 141 from the die receptacle 117 by grasping the stick 142.

The take-up mechanism 175 (Figures 1-9-10 and 11) comprises a vertical shaft 176 which is journaled in ball bearing raceways 177-178 provided in split bearings 179-180 (Figure 9). The split bearing 179-180 is supported by a frame extension 181 formed integral with the frame 11. A tubular boss 182 extends upwardly from the table top extension 181 to provide a peripheral cam edge 183 upon which cam following rollers 184, in this instance four, traverse for contact therewith. The rollers 184 are journaled on studs 185 which are anchored in pivotal mounts 186 that extend between furcated radial brackets 187 that are fixed to the vertical shafts 176.

A plurality of bolts 188, in this instance four, extend transversely through the furcated brackets 187 to pivotally support the roller mounts 186 relative to the vertical shaft 176 (Figure 9). The pivotal mounts 186 carry radially extending quadrants 189, in this instance four, which are attached to the mounts 186 to pivot relative to a circular plate 190. The circular plate 190 is associated with the shaft 176 for rotation therewith through a key 191 provided between the shaft 176 and the plate 190. The pivotal movement of the quadrants 189 relative to the plate 190 is effected responsive to the rotation of the shaft 176 which carry the rollers 184 over the peripheral cam edge 183 to raise and lower the quadrant supporting mounts 186 so that the preformed candies 141 with their sticks 142 are grasped between the quadrants 189 and the plate 190 in timed rotation of the take-up mechanism 175 that is synchronized with the rotation of the confronting dies 122-123 and their supporting mechanism 109-110 constituting a rotary table member.

The relative speed of rotation of the take-up mechanism 175 through the shaft 176 is such that the preformed candies 141 with their sticks 142 arrive as the quadrants 189 are elevated proximate to the plate 190 in their upward pivotal movement to grasp the candy sticks 142 therebetween and thus successfully remove them along a circular path for consequent release at a discharge point where a receptacle is positioned to

receive the finished products 141—142. To this end, the lower surface of the circular plate 190 is chamfered as at 192 along the peripheral edge thereof to conform with the angularity of the quadrants 189 when the latter are elevated to their extreme grasping position against the plate 190 with the sticks 142 therebetween (Figure 9).

The circular plate 190 is urged downwardly against a stop 193 on the shaft 176 by means of a spring 194 which envelops the shaft 176 for engagement with a bushing 195 at its lower extremity. The bearing 195 is associated with a shaft 176 for rotation therewith through the medium of the key 191 to support the spring 194 and downwardly urge the plate 190 during the rotation thereof. The spring 194 is anchored at its upper end by means of a collar 196 fixed to the shaft 176 through a suitable fastener such as the set screw 197 to provide for adjustment along the shaft 176 to control and adjust the compression in the spring 194, and thus regulate the friction grasp of the sticks 142 to effect the removal of the preformed candy unit 141 therewith. As the plate 190 and the quadrants 189 rotate in a clockwise direction (viewed from Figure 1), the quadrants 189 gradually descend the grasp of the sticks 142 which together with their candy balls or units 141 are displaced through the inertia of rotation for collection in a tumbler or other processing unit or ordinary collection receptacle for packaging.

The continued clockwise rotation of the table or die supporting members 109—110 (viewed from Figure 1) beyond the take-up mechanism 175 prepares the confronting dies 122—123 to assume their initial position preparatory to reaching the stick supplying station 198. So that any candy units 141 which accidentally passed around and beyond the take-up mechanism 175 without sticks 142, may be removed prior to reaching the stick supplying station 198, a scraper blade 199 is provided to reciprocate above and in close proximity to the lower die mounting table 109 (Figures 1, 18 and 19).

The scraper 199 has a normally offset shank 200 (Figure 1) which reciprocates in guides 201—202 fixed to the upper surface of the frame 11. A link 203 is pivoted to the scraper shank 200 as at 204 for pivotal connection to a longitudinal link 205 which is anchored to the frame top 11 as at 206. An intermediate transverse link 207 is pivoted to the longitudinal link 205 as at 208. The transverse link 207 is operatively connected to a rotating vertical crank 209 which oscillates the link 205 and reciprocates the scraper 199 through its shank 200 and its connecting link 203. The crank 209 extends downwardly through the frame top 11 for rotation responsive to the driving mechanism which will be hereinafter described. The feeding of sticks 142 at the hopper or stick feeding station 198 is synchronized with the continuous rotation of the die supporting elements 109—110.

In order to automatically supply the handle sticks 142 to the lower die element 122 and to effect the support thereof at the desired elevation with respect to the concavity or shape of the complementary die elements 122—123, the stick slots 136—137 are provided to extend in the radially outer peripheral surface 137 of the lower table die mount 109 which is slotted as at 136—139 (Figure 6) in radial diametrical alignment with each of the lower dies 122. The radial stick slots 136—139 communicate with each of the die receptacles 117 provided in the lower table 75

mount 109, and each of the lower die receptacles 117 is provided with corresponding slots 139 which align with the table mount slots 136 to receive the sticks 142 at approximately the same elevation as the top of the lower die elements 122 when it is in its initial lowermost position in the die body 117 (Figure 6). With this arrangement, the candy segments 69 (Figure 13) will be deformed by both complementary dies 122—123 into the shape of the latter around the inward extremity of the sticks 142 responsive to the depression of the upper die element 123.

The sticks 142 are confined in a hopper 210 (Figures 1, 14 and 15) that has a converging side wall depending extension 211—212 defining a restricted discharge open bottom 213 that defines an arcuate lower end conforming to and communicating with a cylindrical stick distributing drum 214. The arcuate hopper bottom 213 has its opening along the length thereof which substantially conforms with and is somewhat narrower than the circumferential spacing of straight transverse slots 215 on the periphery of the drum 214. The stick distributor in the form of a cylindrical drum rotor 214 is journaled on a shaft 216 for rotation therewith to bring the slotted periphery of the drums 214 adjacent the correspondingly shaped hopper bottom 213. The shaft 216 is fixed to the rotor or drum 214, and is journaled in bearing raceways 217—218 provided in the hopper assembly to support the shaft 216 for rotation with a sprocket wheel 219 having a chain 220 meshing therewith. Consequently, the sticks 142 confined in the hopper 210 will be distributed for individual deposit in the transverse slots 215 of the distributor drum 214 which, in turn, cooperate with stick retainers 221 (Figures 14 and 22) provided in radial alignment with each of the lower dies 122 for attachment to the outer periphery of the lower die mount 109.

The sticks 142 are stacked in the hopper 210 which is provided with a driven knurled rod 222 journaled in the hopper side walls 223—224 (Figure 15). The rotation of the knurled rod 222 serves as a stick repeller to preclude the bunching of the sticks 142 and provide for their deposit in the drum slots 215. The sticks 142 that are lodged in the slots 215 are therein retained until displaced to the retainers 221 therebelow (Figure 14), and a loosely disposed ring 225 confined in a peripheral groove 226 on the drum hub 227, rides over the stick retainers 221. The loosely rolling ring 225 precludes the sticks 142 from being accidentally displaced at the time of their transition from the drum slots 215 to the retainers 221 and momentarily until the latter grasp the sticks 142 as will presently appear.

The sticks 142 are dropped into the retainers 221 which, in this instance, comprise a tubular sleeve 228 (Figures 21 and 22) having a downwardly offset boss 229 for attachment to the depending outward peripheral wall 230 (Figures 6 and 21) of the lower table mount 109. The sleeve 228 has upstanding stick guides 231—232, in this instance two, which are formed integral therewith (Figure 22) to serve as stops against which the sticks 142 are forcibly held by means of a cam actuated arcuate finger 233 mounted for operation responsive to an arm 234 that is pivoted on a pintle 235 anchored in the sleeve boss 229 (Figure 21). A roller 236 is journaled on the pintle 235 to rotatively support the stick retainers 221 on a plate extension 237 projecting from the lower table mount 109.

The finger arm 234 has a cam follower arm

238 extending therefrom beyond the pintle 235 to carry a cam roller 239 (Figure 1) in confronting relation with and in the path of a cam 240 to open the finger 233 relative to the stick guides 231—232. A spring 241 (Figure 22) normally urges the finger 233 toward the fixed stick guides and stops 231—232 while the fixed table cam 240 serves to separate the finger 233 relative to the fixed guides and stops 231—232 against the urge of the spring 241 to vertically receive the sticks 142 from the hopper 210 and permit the horizontal displacement of the sticks 142 therefrom for impaling the candy 141. The sticks 142 are displaced from the retainers 221 in a horizontal direction toward and through the slots 137—139 in the lower table mount 109 and die receptacle 122 (Figure 6).

This is accomplished by means of a cam follower 243 fixed to the extremity of a rod 244 (Figures 1 and 21) which telescopes into a sleeve 245 that, in turn, telescopes into the sleeve 228. The rod 244 and sleeve 245 each have flanged ends 246 and 247 which are in the path of peripheral shoulders 248 and 249 provided internally within the sleeves 245 and 228, respectively, to preclude the separation of the stick retaining and impaling mechanism 221. The cam follower 243 has a rounded external surface (Figure 1) which abuts against a fixed arcuate cam track 251 fixed by brackets 252—253 and fasteners 254 to the frame top 11. The cam 251 gradually displaces the stick 142 inwardly until the retainers 221 arrive at approximately one-half revolution from the stick feeding hopper 210 (Figure 1), and in that range of movement another cam track 255 (Figures 1 and 17) is adjustably mounted as at 256—257 (Figure 1) to the frame mounted bracket 152 to finally impale the stick 142 into the preformed candy 141. The cam track 255 is radially adjustable at its mounts 256—257 to accommodate different lengths of stick 142.

The inward surface 258 of the cam followers 243 is flat to cooperate with a fixed cam track 259 (Figure 1) which serves to separate the telescopic elements 244—245 to their maximum extent opposite to their fully telescoped impalement position, to make ready for a repetition of the impalement function. During this time the cam follower 236 (Figure 21) rides the high side of the cam 240 to recede the stick engaging finger 233 from the fixed guides and stops 231—232 to thus open the retainers 221 for the reception of a stick 142 as their position of movement is in the path of the hopper 210. The stick distributor drum 214 is rotarily adjustable by means of the oppositely disposed threaded studs 260—261 that are provided on a plate 262 for engagement with a pin 263 anchored in the side of the drum 214. Locking studs 264—265 are threadedly anchored in the drum 214 to extend through arcuate slots 266—267 provided in the plate 262 which comprises part of a sprocket wheel 219 for rotating the drum 214. The hopper 210 and its assembled elements are mounted on a standard 268 that is supported by the frame top 11. The hopper 210 is rigidly supported so that its bottom discharge slot overlies and is in the path of the transverse slots 215 provided in drum 214 which transfers the sticks 142 to the retainers 221 as such rotate thereunder with the lower die mount 109.

With this arrangement, the sticks 142 are deposited in the drum slots 215 and as the lower die mount 109 rotates, the stick is carried in the retainers 221 therewith for horizontal inward

displacement for the desired distance so that the inward stick extremity registers with the axis of the lower die element 122. The feeding of the sticks 142 is effected responsive to the rotation of the hopper rotor or drum 214 in timed relation with the rotation of the table mounts 109—110 and the other operating instrumentalities as will appear more fully hereinafter.

The instrumentalities thus far described are operated in timed relation from a common power source constituting an electric motor 269 (Figure 2) fixed to a bottom frame plate supported by the standards 12. The motor 269 is coupled as at 239 to a speed reducer 270 (Figures 2 and 3) which is also fixed to the bottom frame plate so that the driven shaft 274 thereof imparts the desired speed of rotation to a sprocket pinion 271 that is in alignment with sprocket wheel 272 fixed to a shaft 273 for connection through a chain 274. The shaft 273 is journalled in the bearing brackets 275—276 that are attached through any suitable fasteners 277 to the bottom frame plate to rotatably support the shaft 273 for driving the various instrumentalities in timed relation as will be presently described. The eccentric crank arm 37 is fixed to the shaft 273 to oscillate the connecting rod 36 which operates the bell crank arm 35 (Figure 5) to intermittently rotate the shaft 33, this being accomplished through the pawl 34 which cooperates with the ratchet wheel 33 to impart corresponding intermittent rotation to the candy feed rollers 44—45 (Figures 2—3—20). The operation of the candy feed roller 44—45 in timed relation with the knives 41—42 and their associated elements has been described supra.

As shown, the main shaft 273 (Figure 3) has a pinion 278 fixed thereto adjacent to the bearing 276 to mesh with a spur gear 279 fixed to a countershaft 280 disposed parallel to the main shaft 273. The countershaft 280 is journalled in bearings 281—282 fixed to the underside of the frame top 11. The countershaft 280 carries a bevel pinion 283 which meshes with a bevel gear 284 that is fixed to a vertical shaft 189 to which the table mounts 109—110 are fixed for continuous rotation therewith. The countershaft 280 and the vertical shaft 189 geared thereto, rotate continuously to carry the circumferentially spaced series of complementary die members 122—123 along a circular path in timed relation with the other instrumentalities described for operation in connection therewith.

The bevel gear 284 meshes with another bevel pinion 285 fixed to a stub shaft 286 disposed normally thereto and journalled in a bearing 287 fixed to the underside of the frame top 11 to carry a bevel gear 288. The bevel gear 288 meshes with a bevel pinion 289 which is fixed to the vertical shaft 189 to continuously rotate the stick grasping and ejecting instrumentalities 175 (Figures 3—9). The bevel gear 284 also meshes with another bevel pinion 290 disposed diametrically opposite to the bevel pinion 285 (Figure 3) for attachment to a stub shaft 291 journalled in bearings 292—293 fixed to the underside of the frame top 11. A stub shaft 291 carries another bevel pinion 294 which meshes with a bevel gear 295 fixed to the vertical shaft 87 that rotatively supports the candy segment distributor 79 (Figure 1) described supra.

The main driven shaft 273 also carries a bevel gear 296 that is attached thereto to mesh with spaced parallel normally disposed bevel gears 297—298 (Figure 3) fixed to the adjacent ex-

tremities of aligned shafts 299—300, respectively, journalled in bearings 301, 302 and 303, respectively. The shaft 299 has a spur gear 304 attached to the extremity thereof beyond bearing 302 to mesh with a spur pinion 305 that is attached to a stub shaft 306 to carry a bevel gear 307. The bevel gear 307 meshes with a bevel gear 308 fixed to a vertical shaft 299 to operate the scraper 199 described supra (Figure 1). The aligned stub shaft 306 carries a bevel gear 309 which meshes with a bevel gear 310 fixed to a vertical shaft 311 which is journalled in a bearing 312 fixed to the table top 11 (Figure 23) to support a bevel gear 313 that meshes with another bevel gear 314 fixed to the knife operating cam shaft 56 described supra. It should be observed that the main driven shaft 273 carries a pulley 315 over which a belt 316 extends to operate a pulley 317 fixed to the stick repeller 222. This provides for dependable distribution of sticks 142 to the distributor drum 214.

The main driven shaft 273 is operatively connected to the countershaft 280 through the gears 278—279. To enable the disconnection of the shafts 273—280, a clutch element 318 is provided to idle on the countershaft 280. The clutch element 318 is complementary to another clutch element 319 associated with the countershaft 280 for rotation therewith and slidably therealong so that the clutch element 319 may be caused to engage or disengage the clutch element 318 through the medium of a yoke 320 (Figure 4). The yoke 320 has aligned trunnions 321—322 cooperating with an angular groove 323 provided on hub 324 of the clutch element 319. The yoke 320 is pivoted to a link 325 which carries a bearing 326 for attachment to a rod 327 that is journalled in bearing brackets 328—329 fixed to the frame 10 (Figures 2 and 4). The rod 327 has a handle member 330 fixed to the extremity thereof to enable the fractional rotation of the clutch operating shaft 327 to cause the clutch elements 318—319 to be in effective complementary engagement or disengagement so that the motor 268 may continue to operate while the remaining instrumentalities such as the table mounts 109—110 together with all other associated elements are rendered inoperative for adjustment, cleaning, or other service requirements. The handle 330 is readily accessible to control the operation of the clutch 318—319. The idler clutch element 318 carries a sprocket wheel 331 (Figure 3) that drives a sprocket chain 220 which, as described supra, operates the hopper distributor drum 214 so that these elements are rendered inactive when the clutch elements 318—319 are separated.

While we have illustrated and described a preferred embodiment of this invention, it must be understood that the invention is capable of considerable variation and modification without departing from the spirit of the invention. We, therefore, do not wish to be limited to the precise details of construction set forth, but desire to avail ourselves of such variations and modifications as come within the scope of the appended claims.

We claim:

1. In a device of the character described, the combination with a frame, of a table mounted for continuous rotation on said frame, a plurality of pairs of normally separated complementary die members uniformly spaced on said table, means for feeding material to said complementary die members when in separated relation, means for displacing one complement of said die mem-

bers toward the other to compress the material therein, means for returning said compressing die member complement to its initial position, and rotary clutching means for removing the preformed material from said die member after the compressing die is elevated.

2. In a device of the character described, the combination with a frame, of a table mounted for continuous rotation on said frame, a plurality of pairs of normally separated complementary die members uniformly spaced on said table, springs for normally urging said complementary die members from each other, means for feeding material to said complementary die members when in separated relation, means for displacing one complement of said die members toward the other to compress the material therein, means for returning said compressing die member complement to its initial position, and axially mounted means rotating in timed relation to said table to remove the preformed material from said complementary die members.

3. In a device of the character described, the combination with a frame, of a table movably mounted for continuous rotation on said frame, a plurality of pairs of normally separated complementary superposed die members uniformly spaced on said table, means for successively feeding material to said complementary die members when in separated relation, means for displacing one complement of said die members toward the other to compress the material therein, means for returning said compressing die member complement to its initial position, means for displacing sticks into radial alignment with said complementary die members, and means for progressively impaling said radially aligned sticks into the material confined between said table moves on said frame in synchronous timed relation with said stick displacing means.

4. In a device of the character described, the combination with a frame, of a table rotatably mounted for continuous rotation on said frame, a plurality of pairs of normally separated complementary die members uniformly spaced on said table, means for intermittently feeding material to said complementary die members when in separated relation means for cutting said intermittently fed material into segments, while said feeding means are inactive, means for displacing one complement of said die members toward the other to compress the material therein, means for returning said compressing die member complement to its initial position, and axially mounted rotary grasping means for removing the compressed material from the other die member complement.

5. In a device of the character described, the combination with a frame, of a table rotatably mounted for continuous rotation on said frame, a plurality of pairs of normally separated complementary die members uniformly spaced on said table, springs operatively associated with said complementary die members for normally effecting their extreme separation, means for intermittently feeding material to said complementary die members when in separated relation, means for displacing one complement of said die members toward the other to compress the material therein, means for returning said compressing die member complement to its initial position, stick retainer means mounted on said table in radial alignment with said complementary die members, and cam means on said frame cooper-

ating with said stick retainer means for progressively displacing the sticks toward said die members.

6. In a hard candy forming machine, the combination with a frame, of a table rotatively mounted on said frame, a plurality of uniformly spaced pairs of normally separated complemental die members on said table, means for rotating said table on said frame, means for effecting the displacement of continuous lengths of candy toward said table, means for severing said continuous length of candy into segments, means for displacing the candy segments between complemental die members as the table rotates to bring complemental die members in the path of said displacing means, means for moving one die member complement toward the other with the candy segments therebetween for effecting the compression and shaping of said segments, stick retainer means in radial alignment with each of said complemental die members, stick feeding means disposed above the path of said stick retainer means, means for opening and closing said stick retainer means as said table rotates therewith to receive and engage sticks from said stick feeding means, and means associated with said stick retaining means to radially translate the sticks toward said complemental die members to impale the candy segments.

7. In a hard candy forming machine, the combination with a frame, of a table rotatively mounted on said frame, a plurality of uniformly spaced pairs of normally separated complemental die members on said table, radially disposed stick retaining means on said table in radial alignment with each of said pairs of complemental die members, means for feeding non-edible sticks to said stick retaining means with a portion thereof disposed between said complemental die members, means for rotating said table on said frame, means for effecting the displacement of continuous lengths of candy toward said table, means for severing said continuous length of candy into segments, means for displacing the candy segments between complemental die members as the table rotates to bring complemental die members in the path of said displacing means, means for moving one die member complement toward the other with the candy segments therebetween for effecting the compression and shaping of said segments around said sticks, and cam means on said frame for progressively displacing the sticks from said stick retaining means into said complemental die members to impale the candy segments as said table rotates.

8. In a hard candy forming machine, the combination with a frame, of a table rotatively mounted on said frame, a plurality of uniformly spaced pairs of normally separated complemental die members on said table, spring means for normally maintaining said complemental die members in spaced relation, means for feeding non-edible sticks to said table with a portion thereof disposed between said complemental die members, means for rotating said table on said frame, means for effecting the displacement of continuous lengths of candy toward said table, means for severing said continuous length of candy into segments, means for displacing the candy segments between complemental die members as the table rotates to bring complemental die members in the path of said displacing means, means for moving one die mem-

ber complement toward the other with the candy segments therebetween for effecting the compression and shaping of said segments around said sticks, stick feeding means disposed above the path of said complemental die members, a rotary stick distributor drum in said stick feeding hopper means, stick retainer means on said table in radial alignment with said complemental die members, cam means for displacing said sticks into said die member to impale the candy segments, and rotary stick grasping means for removing the preformed candy from said complemental die members.

9. In a hard candy forming machine, the combination with a frame, of a table rotatively mounted on said frame, a plurality of uniformly spaced pairs of normally separated complemental die members on said table, means for rotating said table on said frame, intermittent means for effecting the displacement of continuous lengths of candy toward said table, confronting movable means for severing said continuous length of candy into segments, candy holding means operable momentarily prior to said severing means, means for displacing the candy segments between complemental die members as the table continuously rotates to bring complemental die members in the path of said displacing means, stick supply means mounted on said frame above the path of travel of said complemental die members, stick retainer means in radial alignment with each of said complemental die members, cam means for opening and closing said stick retainer means, and cam means for operating said complemental die members.

10. In a hard candy forming machine, the combination with a frame, of a table rotatively mounted on said frame, a plurality of uniformly spaced pairs of normally separated complemental die members on said table, means for rotating said table on said frame, intermittent means for effecting the displacement of continuous lengths of candy toward said table, means for severing said continuous length of candy into segments, knocker means for displacing the candy segments between complemental die members as the table rotates to bring complemental die members in the path of said displacing means, a stick feeding hopper on said frame above the path of travel of said complemental die members, stick distributor means in said hopper, stick retainer means on said table to receive the sticks from said distributor, and means associated with said stick distributor means for momentarily resting on the sticks as they are deposited in said stick retainer means.

11. In a hard candy forming machine, the combination with a frame, of a table rotatively mounted on said frame, a plurality of uniformly spaced pairs of normally separated complemental die members on said table, means for rotating said table on said frame, intermittent means for effecting the displacement of continuous lengths of candy toward said table, means for severing said continuous length of candy into segments, means for displacing the candy segments between complemental die members as the table rotates to bring complemental die members in the path of said displacing means, a stick feeding hopper on said frame above the path of travel of said complemental die members, stick distributor means in said hopper, stick retainer means on said table to receive the sticks from said distributor, means associated with said stick distributor means for momentarily resting on the sticks as

they are deposited in said stick retainer means, and means for closing and opening said stick retainer means.

12. In a hard candy forming machine, the combination with a frame, of a table rotatably mounted on said frame, a plurality of uniformly spaced pairs of normally separated complemental die members on said table, means for rotating said table on said frame, intermittent means for effecting the displacement of continuous lengths of candy toward said table, means for severing said continuous length of candy into segments, means for displacing the candy segments between complemental die members as the table rotates to bring complemental die members in the path of said displacing means, a stick feeding hopper on said frame above the path of travel of said complemental die members, stick distributor means in said hopper, stick retainer means on said table to receive the sticks from said distributor, means associated with said stick distributor means for momentarily resting on the sticks as they are deposited in said stick retainer means, means for closing and opening said stick retainer means, plungers associated with said stick retainer means, and means for displacing said stick retainer plungers to impale the sticks into the candy segments during the preforming thereof.

13. In a hard candy forming machine, the combination with a frame, of a table rotatably mounted on said frame, a plurality of uniformly spaced pairs of normally separated complemental die members on said table, means for rotating said table on said frame, intermittent means for effecting the displacement of continuous lengths of candy toward said table, means for severing said continuous length of candy into segments, knocker means for displacing the candy segments between complemental die members as the table rotates to bring complemental die members in the path of said displacing means, a stick feeding hopper on said frame above the path of travel of said complemental die members, stick distributor means in said hopper, stick retainer means on said table to receive the sticks from said distributor, means associated with said stick distributor means for momentarily resting on the sticks as they are deposited in said stick retainer means, means for closing and opening said stick retainer means, plungers associated with said stick retainer means, means for displacing said stick retainer plungers to impale the sticks into the candy segments during the preforming thereof, and stick grasping means for removing the preformed impaled candy from said complemental die members.

14. In a device of the character described, the combination with a frame, of a table rotatably mounted on said frame, a plurality of complemental die members circumferentially spaced on said table, radial stick receiving slots in said table between the outer periphery and said die members, confronting candy feeding rollers on said frame for displacing a continuous ribbon of candy toward said table, reciprocally mounted severing means in the path of said feeding rollers for segmenting the continuous ribbon of candy, knocker means for transferring the severed segments to said complemental die members, means for operating said complemental die members to compress the segments around the sticks and effect the ejection thereof from said die members, and axial mounted rotating clamping means for grasping said stick impaled candy to effect the

removal thereof from said complemental die members.

15. In a device of the character described, the combination with a frame, of a table rotatably mounted on said frame, a plurality of complemental die members circumferentially spaced on said table, to receive candy segments radial stick receiving retainers on said table between the outer periphery and said die members, hopper means for confining a supply of sticks above said table, means for successively transferring sticks from said hopper to said retainers, cam means for radially displacing the sticks from said retainers to impale the candy segments, confronting candy feeding rollers on said frame for displacing a continuous ribbon of candy toward said table, reciprocally mounted severing means in the path of said feeding rollers for segmenting the continuous ribbon of candy, knocker means for transferring the severed segments to said complemental die members, means for operating said complemental die members to compress the segments around the sticks and effect the ejection thereof from said die members, scraper means for removing defective candy segments after the compression of said complemental die members, and stick grasping means for removing the preformed impaled candy segments from said complemental die members.

16. In a device of the character described, the combination with a frame, of a table rotatably mounted on said frame, a plurality of complemental die members circumferentially spaced on said table, radial stick receiving means on said table between the outer periphery and said die members, spring means for normally maintaining said complemental die members in confronting spaced relation, hopper means for confining a supply of sticks above said table, means for successively transferring sticks from said hopper to said stick receiving means with a portion thereof extending into said complemental die members, impaling means associated with said table for endwise contact with sticks disposed in said stick receiving means, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members, and means for operating said complemental die members to compress the segments around the sticks and effect the ejection thereof from said die members.

17. In a device of the character described, the combination with a frame, of a table rotatably mounted on said frame, a plurality of complemental die members circumferentially spaced on said table, radial stick receiving means on said table between the outer periphery and said die members, spring means for normally maintaining said complemental die members in confronting spaced relation, hopper means for confining a supply of sticks above said table, a slotted drum in said hopper means, means for successively transferring sticks from said slotted drum into said stick receiving means with a portion thereof extending into said complemental die members, cam actuated impaling means associated with said table for endwise contact with sticks disposed in said stick receiving means, confronting candy feeding rollers on said frame for displacing a continuous ribbon of candy toward said table, reciprocally mounted severing

means in the path of said feeding rollers for segmenting the continuous ribbon of candy, means for transferring the severed segments to said complemental die members, and cam means for operating said complemental die members to compress the segments around the sticks and effect the ejection thereof from said die members.

18. In a device of the character described, the combination with a frame, of a table rotatably mounted on said frame, a plurality of complemental die members circumferentially spaced on said table, radial stick receiving means on said table between the outer periphery and said die members, complemental stick grasping jaws on said stick receiving means, spring means for normally maintaining said complemental die members in confronting spaced relation, hopper means for confining a supply of sticks above said table, cylindrical drum means for successively transferring sticks from said hopper to said stick receiving means with a portion thereof extending into said complemental die members, means for operating said stick receiving means to open and close said stick grasping jaws, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members, stationary cam means responsive to the rotation of said table for operating said complemental die members to compress the segments around the sticks, and rotary stick grasping means for removing the finished impaled candy segments from said die members.

19. In a device of the character described, the combination with a frame, of a table rotatably mounted on said frame, a plurality of complemental die members circumferentially spaced on said table, radial stick receiving retainers on said table between the outer periphery and said die members, spring means for normally maintaining said complemental die members in confronting spaced relation, hopper means for confining a supply of sticks above said table, means for successively transferring sticks from said hopper to said stick receiving retainers with a portion thereof extending into said complemental die members, confronting candy feeding rollers on said frame for displacing a continuous ribbon of candy toward said table, means for intermittently rotating said feeding rollers, reciprocally mounted severing means in the path of said feeding rollers for segmenting the continuous ribbon of candy, means for transferring the severed segments to said complemental die members, cam means on said table in the path of sticks disposed in said stick receiving means for impaling the sticks into the candy segments, and stationary cam means responsive to the rotation of said table for operating said complemental die members to compress the segments around the sticks.

20. In a device of the character described, the combination with a frame, of a table rotatably mounted on said frame, a plurality of complemental die members circumferentially spaced on said table, radial stick receiving retainers on said table between the outer periphery and said die members, impaling means associated with said stick receiving retainers, spring means for normally maintaining said complemental die members in confronting spaced relation, hopper

means for confining a supply of sticks above said table, means for successively transferring sticks from said hopper to said stick receiving retainers with a portion thereof extending into said complemental die members, confronting candy feeding rollers on said frame for displacing a continuous ribbon of candy toward said table, reciprocally mounted severing means in the path of said feeding rollers for segmenting the continuous ribbon of candy, means for transferring the severed segments to said complemental die members, stationary cam means fixed to said frame above and below said complemental die members for operating said complemental die members against the urge of said spring means to compress the segments around the sticks, and stationary cam means on said table for end-wise contact with the sticks for actuating said impaling means to transfer the sticks from said stick retainers into the candy segments while confined in said complemental die members.

21. In a device of the character mentioned, the combination with a rotatable table, of a plurality of uniformly spaced complemental die members on said table for preforming edible segments in conjunction with extending non-edible handles, another axially mounted rotatable member substantially in the plane of said rotatable table, a plurality of handle clamping means uniformly spaced on said last named rotatable member, and means for opening and closing said clamping means responsive to the rotation of said rotatable member in synchronous relation with the rotation of said table to grasp the handles on said preformed edible segments for effecting the removal thereof from said complemental die members.

22. In a device of the character mentioned, the combination with a rotatable table, of a plurality of uniformly spaced complemental die members on said table for preforming edible segments in conjunction with extending non-edible handles, another axially mounted rotatable member substantially in the plane of said rotatable table, a plurality of handle clamping means uniformly spaced on said last named rotatable member, means for continuously rotating said table and rotatable member in timed relation so that they provide substantially the same circumferential speed between the overlapping handles and clamping means, and means for opening and closing said clamping means responsive to the rotation of said rotatable member in synchronous relation with the rotation of said table to grasp the handles on said preformed edible segments for effecting the removal thereof from said complemental die members.

23. In a device of the character mentioned, the combination with a rotatively mounted table, a plurality of uniformly spaced pairs of normally separated complemental die members on said table, radially disposed stick clamping means on said table for each pair of complemental die members, means for opening and closing said stick clamping means responsive to the rotation of said table, means for feeding non-edible sticks to said clamping means while open in radial alignment with said complemental die members, means for displacing said sticks within said complemental die members as said table rotates and while said clamping means are open, and means for momentarily resting on said sticks while said clamping means are open and during the initial displacement of said sticks within said complemental die members.

24. In a device of the character mentioned, the combination with a rotatively mounted table, a plurality of uniformly spaced pairs of normally separated complementary die members on said table, radially disposed stick clamping means on said table for each pair of complementary die members, means for opening and closing said stick clamping means responsive to the rotation of said table, means for feeding non-edible sticks to said clamping means while open in radial alignment with said complementary die members, means for displacing said sticks within said complementary die members as said table rotates and while said clamping means are open, and loosely suspended ring means on said stick feeding means for momentarily resting on said sticks while said clamping means are open and during the initial displacement of said sticks within said complementary die members.
